UNITED STATES PATENT OFFICE

JULIUS RITTER, JR., OF RACINE, WISCONSIN, ASSIGNOR TO HARTMANN TRUNK COMPANY, OF RACINE, WISCONSIN, A CORPORATION OF WISCONSIN

WARDROBE-CONTAINER DISENGAGEABLE HINGE

Application filed September 22, 1928. Serial No. 307,737.

This invention relates to improvements in wardrobe container disengageable hinges. It is one of the objects of the present invention to provide in a two-section wardrobe container, means carried by one of the sections hingedly engaging the other section, and also disengageable from the other section, when the sections are open with respect to each other, to permit the complete separation of said sections for convenience in packing and storing.

A further object of the invention is to provide in a two-section container, hinge members of the class described, which, when one section is being moved to closed position, exert a drawing force to tightly and securely pull the adjacent portions of the container together and insure the complete closure of the same.

20 A further object of the invention is to provide container section hinge members, which, when the container is closed, act as end bracing and reinforcing members preventing the container from bulging and also holding the cover section securely in engagement with the other section.

A further object of the invention is to provide container disengageable hinges of the class described which are of very simple construction, are inexpensive to manufacture, are strong and durable, and are well adapted for the purpose described.

With the above and other objects in view the invention consists of the improved wardrobe container disengageable hinges, and their parts and combinations as set forth in the claims, and all equivalents thereof.

In the accompanying drawing in which the same reference characters indicate the same parts in all of the views:

Fig. 1 is a vertical sectional view of a wardrobe case in open position with the case sections detachably connected by the improved hinge members;

Fig. 2 is a fragmentary sectional view on a larger scale of the adjacent portions of the case sections in open position, showing a hinge member and also showing in dotted lines the detachment of one section;

Fig. 3 is an enlarged sectional view of the case sections in closed position; and

Fig. 4 is an enlarged inner end view of the case section which carries the hinge members.

Referring now more particularly to the drawing, it will appear that the numeral 6 indicates a wardrobe case or container having a lower right angular extension 7, and a cover section 8 adapted to close the wardrobe section 7.

The invention resides particularly in the means for disengageably hingedly connecting the inner end portion of the cover section 8 to the end wall 9 of the extension 7' of the body section 7. For that purpose there are secured against the lower inner side walls of the cover section a pair of hook hinges indicated generally by the numeral 10. As clearly shown, each hook hinge has an inner shank or plate portion 11 secured to the lower inner portion of a side wall 12 of the section 8, and an outer hook portion 13 extending from the inner end of said section 8. Each hook portion has an upper rounded edge 14 and a lower recessed edge 15.

When the container or case sections are open with respect to each other, the section 8 is disposed in the manner shown in Figs. 1 and 2 with the hook portions 13 resting on the upper edge of the end wall 9 of the extension 7', said wall edge lodging within the lower edge recess 15 of the hook portions. From this position the section 8 may be lifted to a position of complete disengagement and separation from the section 7, as indicated by the dotted lines in Fig. 2, for convenience in packing.

The closure of the case from open position is effected in the usual manner, with the hook hinges moving on the edge of the wall 9 and the outer end portion of the section 8 being pushed toward the section 7. During this movement, the curved or recessed lower edge portion 15 of the members 10 ride inwardly on the wall edge, pulling the adjacent portions of said sections together until, when the sections are completely closed, the hook hinges are in the position shown in Fig. 3.

with each hook end portion 16 bearing against the wall 9.

It will thus be seen that the improved disengageable hinges permit the complete easy separation of a pair of container sections, and also, when one section is being closed with respect to the other section, said hinges exert a drawing force, insuring a proper and tight closure of the container sections. In addition, when the container is closed, said hinge members bear against the end wall 9 and brace and reenforce the same. Also, the disengageable hinges for containers are simple and novel in construction, and are well adapted for the purposes set forth.

What is claimed as the invention is:

1. In a hand luggage case having a pair of walled sections, one-piece hinge members disengageably connecting said sections, said hinge members being secured to an end portion of one section and having outwardly projecting hook portions formed with inwardly curved lower edge recesses and rounded outer end portions, a plane edge of the end wall 25 of the other section being freely engaged within said curved edge recesses.

2. In a hand luggage case having a pair of walled sections, one-piece hinge members disengageably connecting said sections, said hinge members being secured to an end portion of one section and having outwardly projecting hook portions formed with inwardly curved lower edge recesses and rounded outer end portions, an edge of the end wall of the 35 other section being freely engaged within said curved edge recesses when the sections are open with respect to each other, and said hinge members bearing against the inner surface of an end wall of said other section inferiorly of said section when the sections are 40 closed with respect to each other.

3. In a luggage carrier, a body section comprising an upright portion and a horizontal portion cooperating therewith to form a substantially L-shaped chamber, and a cover section cooperable with said body portion to form a complete enclosure, said cover section having a hinge member attached to the lower portion thereof closely adjacent to each of 50 its opposite sides, and said hinge members coacting with the end wall of said horizontal portion closely adjacent to the side walls of said portion when said sections are in closed position and being freely vertically removable from the top of said end wall when said cover section is open.

4. In a luggage carrier, a body section comprising an upright portion and a horizontal portion cooperating therewith to form a substantially L-shaped chamber, and a cover section cooperable with said body portion to form a complete enclosure, said cover section having a hinge member attached to the lower portion thereof closely adjacent to each of 60 its opposite sides, and said hinge members

coacting with both the top and with a lower inner side surface of the end wall of said horizontal portion closely adjacent to the side walls of said portion when said sections are in closed position.

In testimony whereof, I affix my signature.
